UNITED STATES PATENT OFFICE.

JACOB S. THORN, OF PHILADELPHIA, PENNSYLVANIA.

DESIGN FOR A SHINGLE OR ROOFING-PLATE.

SPECIFICATION forming part of Design No. 18,591, dated September 4, 1888.

Application filed August 8, 1888. Serial No. 282,254. Term of patent 14 years.

To all whom it may concern:

Be it known that I, JACOB S. THORN, of the city and county of Philadelphia, State of Pennsylvania, have invented and produced a new and original Design for Metallic Roofing-Plates or Shingles, of which the following is a specification, reference being had to the accompanying drawings, which form a part thereof, and in which—

10 Figure 1 is perspective view of my newly-designed roofing-plate, and Fig. 2 a side view of the same, these two views being deemed necessary to fully illustrate my design.

15 My new design consists of a roofing-plate having parallel sides terminating in a thickened lower edge of the peculiar outline shown in the drawings—that is, said lower edge is bounded by two short converging straight lines and a third line running across the center line of the shingle, so as to intersect the short converging lines aforesaid, said shingle also having an elongated projection extending along the medial line on its upper surface.

20 A is the face or upper visible part of the shingle, having long straight sides *a a*, running parallel to the medial line of the shingle.

25 B is the raised or struck-up lower edge of the shingle, bounded by the short converging sides *b b* and the intersecting line *b'*, running across the medial line of the shingle.

C is the elongated elevated boss, formed, as shown, along the medial line of the shingle.

D indicates the upper portion of the visible face of the shingle, which is generally only outlined clearly when coupled with similar shingles, and therefore forms no part of my design. 35

The dotted lines *d d* indicate projecting bosses lying outside of the visible face of the shingle, and the other dotted lines indicate 40 flanges, edges, &c., which may be of any form and construction without in any way affecting my design.

I claim—

45 The design for a metallic shingle or roofing-plate herein shown and described, the same consisting of a shingle having elongated sides running parallel to its medial line, a thickened lower edge bounded by two short straight converging lines and an intersecting line lying 50 across the middle line of the shingle, and having also an elevated elongated projection, C, extending along the medial line of its upper surface.

JACOB S. THORN.
